STUDY CARRELL UNIT

John L. Gianfagna, 102 Crestwood Circle,
Marietta, Ohio 45750

Original design application July 17, 1968, Ser. No. 12,807.
Divided and this application June 5, 1969, Ser. No.
17,530

Term of patent 14 years

Int. Cl. D6—01

U.S. Cl. 73—11

FIG. 1.

FIG. 2.

FIG. 3.

FIG. 1 is a perspective view of a study carrell unit showing my new design;

FIG. 2 is an elevational view taken from a side thereof; and

FIG. 3 is a top view thereof.

This application is a divisional of design application No. 12,807, filed July 17, 1968.

I claim:

The ornamental design for a study carrell unit, substantially as shown.
